ABSTRACT OF THE DISCLOSURE

A machine for simultaneously stamping or punching slotted buttons in sheet metal, as used for attaching air-deflecting vanes or "vane rails" in air duct turns and attaching louver blades to louvers, the device consisting of a support containing a frame structure comprising a horizontally-adjustable sheet metal-receiving work table with a horizontal top plate fixedly-mounted above the work table and provided with an adjustable vertical spindle carrying a bar having a pair of female dies facing downwardly, with means for locking the bar in adjusted rotated position. Another horizontal plate is provided beneath the work table and below this plate is another vertically-movable plate carrying a shouldered member supporting a plurality of vertically-movable dies slidably engaging through apertures provided in the horizontal plate thereabove and being in registry with the female dies. Treadle-operated means consisting of a vertically-movable plunger reciprocates the upstanding male dies vertically to co-act with the female dies. The upwardly-movable member driving the male dies upwardly also carries a guide punch element which indents the sheet metal workpiece. An upstanding guide pin is engageable in the indentation in the next punching and stamping operation to correctly position the workpiece. The dies are formed to create upwardly-stamped buttons and the dies have means to shear the buttons diametrically so as to form slots therein. The dies are adjustable to vary the angle of the slots across the buttons.

This invention relates to stamping and punching machines, and more particularly to a machine for punching slotted buttons in sheet metal as used for attaching turning vanes or "vane rails" in air duct turns and for attaching louver blades to louvers.

A main object of the invention is to provide a novel and improved sheet metal stamping and punching machine for forming slotted buttons in pieces of sheet metal to be employed in ducts, the buttons being used for attaching vanes or louver blades to the sheet metal pieces, the machine being relatively simple in construction, being easy to operate, and providing accurate repetitive fabrication of the desired slotted buttons therein.

A further object of the invention is to provide an improved machine for punching slotted buttons in sheet metal, as used in air ducts and the like, the machine being relatively inexpensive to manufacture, being durable in construction, being adjustable so as to change the locations of the slotted buttons relative to the sheet metal pieces furnished to the machine, as desired, and in accordance with desired locations for fastening vanes or louver blades thereto, and the machine enabling the desired slotted buttons to be quickly and accurately formed with a minimum amount of labor and in an economical manner.

Further objects and advantages of the invention will become apparent from the following description and claims, and from the accompanying drawings, wherein:

FIG. 1 is a fragmentary top plan view of an improved

slotted button stamping and punching machine constructed in accordance with the present invention.

FIG. 2 is a side elevational view, partly broken away, of the machine illustrated in FIG. 1.

FIG. 3 is a horizontal cross-sectional view taken substantially on the line 3—3 of FIG. 2.

FIG. 4 is a vertical cross-sectional view taken substantially on the line 4—4 of FIG. 1.

FIG. 5 is a horizontal cross-sectional view, looking upwardly, taken substantially on the line 5—5 of FIG. 2.

FIG. 6 is a horizontal cross-sectional view taken substantially on the line 6—6 of FIG. 2.

FIG. 7 is a vertical cross-sectional view taken substantially on the line 7—7 of FIG. 1.

FIG. 8 is an enlarged fragmentary vertical cross-sectional detail view taken substantially on the line 8—8 of FIG. 2.

FIG. 9 is a diagrammatic plan view showing a corner turn in an air duct and illustrating in plan view a bottom anchoring plate for receiving the bottom edges of a plurality of curved air-guide plates employed in the corner bend to guide air around the corner of the duct, the anchoring plate being provided with slotted buttons formed by the machine illustrated in FIGS. 1 to 8.

FIG. 10 is a fragmentary plan view of another anchoring plate formed with slotted buttons by the use of the machine of FIGS. 1 to 8, with the slotted buttons having slots in alignment and oriented to receive and support the edges of parallel louvers.

FIG. 11 is an enlarged fragmentary vertical cross-sectional view, generally similar to FIG. 4, and showing an intermediate stage of the working cycle of the machine wherein the male dies are about to engage with the workpiece, the workpiece being clamped against the female dies.

FIG. 12 is a vertical cross-sectional view, similar to FIG. 11, but showing the positions of the male dies after they have penetrated and formed the slotted buttons in the workpiece and showing the cooperation of the male dies with the female dies in the slotted buttons.

FIG. 13 is an enlarged fragmentary vertical cross-sectional view and substantially on the line 13—13 of FIG. 3.

FIG. 14 is a vertical cross-sectional view taken substantially on line 14—14 of FIG. 13.

Referring to the drawings, 14 generally designates an improved device for punching slotted buttons in sheet metal constructed in accordance with the present invention. The device 14 comprises a main supporting plate 15 formed with a depending central cylindrical sleeve portion 16 which is rotatably-received in a vertical cylindrical sleeve-like bushing 17 which is, in turn, supported on a plurality of downwardly-divergent legs 18 secured at their bottom ends to the respective corners of a rectangular base frame 19, the top ends of the legs 18 being rigidly-secured, as by welding or the like, to the sleeve-like bushings 17.

The sleeve 17 is provided with a set screw 20 which may be tightened to lock the inner sleeve 16 and the main supporting plate 15 in an adjusted rotated position relative to the outer sleeve 17.

A vertical plunger or ram member 21 extends slidably through and is vertically-supported by the inner sleeve 16. The bottom end of plunger member 21 is pivotally-connected at 22 to the top end of a coupling bar 23. The bar 23 has a reduced threaded bottom stud portion 24 which is threadedly-engaged in a clevis member 25 whose lower end is pivotally-connected at 26 to the end of a foot lever 27 which is pivoted at 28 to the base frame 19, the connection at 28 being made by a transverse rod which is secured at its ends in opposite sides of the base

frame. Thus, the shorter arm of lever 27 is connected at 26 to the clevis member 25, and the longer arm extends outwardly and is provided at its outer end with a foot pedal pad 29 engageable by the operator's foot, whereby downward pressure on the pad 29 rotates the lever 27 in a clockwise direction, as viewed in FIG. 2, forcing the ram or plunger member 21 upwardly. The top end of the plunger member 21 is reduced, as shown at 30, and engages in a central aperture 31 of a horizontal plate member 32, the reduced portion 30 defining an annular shoulder 33 facing upwardly and which can be used to exert upward force on the plate member 32. Thus, plate member 32 is elevated responsive to the downward movement of the lever pad 29, as above-described.

Designated at 34 is another plate member disposed above the plate member 32 and resiliently-supported on four coiled springs 35 provided at the respective corners of the assembly. Thus, the plate members 15, 32 and 34 are rectangular in shape and are of similar size. Secured to the respective corners of the main supporting plate 15 are upstanding post members 36, and secured to the top ends of the post members 36 is an additional rectangular plate member 37, similar in size and shape to the previously-described plate members 34, 32 and 15. As shown in FIG. 8, the top plate 37 may be secured on the top ends of the post members 36 by respective fastening screws 38 engaged through the corners of the top plate 37 and threadedly-engaged in the top end portions of the post members 36. The post members 36 extend slidably through respective corner apertures 39 and 40 formed in the plate members 32 and 34, the lower ends of the post members 36 being enlarged, as shown at 41 so as to support the plate member 32 in vertically-spaced relationship to the main supporting plate 15, as is clearly shown in FIG. 8. The lower ends of the post members 36 may be secured to the main supporting plate 15 by means of fastening bolts 42, as shown in FIG. 8. The springs 35 surround the post members 36 between the plates 32 and 34, thereby resiliently-supporting the plate 34 in the manner clearly illustrated in FIG. 8.

Plate 34 is secured in an adjusted vertical spacing with respect to plate 32 by the provision of a pair of headed stop bolts 43 and 44 (see FIGS. 4 and 6) located in the longitudinal central plane of the device and symmetrically-disposed on opposite sides of its center line. The bolt 43 engages upwardly through plate 32 and is threadedly-engaged in plate 34, being locked in position by the provision of a lock nut 45 tightened against the bottom surface of plate 34, as shown in FIG. 4. Similarly, the bolt 44 engages upwardly through the plate 32 and is locked to the plate 34 by the provision of upper and lower lock nuts 46 and 47 provided on bolt 44 and engaging the upper and lower surfaces of plate 34. Thus, the stop bolts 43 and 44 have head portions bearing beneath plate 32, thereby limiting the upward movement of plate 34 with respect to plate 32.

The upper plate 37 is formed with a central aperture 48 which is coaxial with plunger member 21. Rotatably-engaged in the aperture 48 is a vertical sleeve member 49 formed integrally at its bottom end with a horizontal bar member 50 provided at its opposite ends with the downwardly-facing female button dies 51, 51. The dies 51, 51 are located at equal radial distances from the axis of sleeve member 49. A horizontal arm 52 is secured to the top portion of the sleeve element 49, the arm 52 being slidably-supported on the top plate 37. Thus, arm 52 may be provided with an aperture 53 at one end portion thereof receiving the top portion of sleeve member 49, the end portion of arm 52 being further provided with a set screw 54 which lockingly-engages the sleeve portion 49, as illustrated in FIGS. 11 and 12. Arm 52 is thus rigidly-connected to the die bar 50, and the position of said die bar is adjusted by correspondingly-adjusting the rotated position of the arm 52. For this purpose, the top plate 37 is formed with a plurality of

10

35

40

45

50

55

60

65

70

detent recesses 53 located at equal radial distances from the vertical axis of rotation of sleeve element 49, said recesses being adapted to selectively-receive the depending pin element 54 provided at the bottom end of a vertical arm 55 integrally-formed on a lever bar 56 pivoted at 57 between a pair of upstanding parallel lugs 58, 58 formed on the outer end portion of arm 52. The lever bar 56 has the upwardly and inwardly-inclined inner arm portion 59 which is pivotally-connected at 60 to the top end of a vertical plunger 61 slidably-engaged in the sleeve member 49 and biased upwardly by a coiled spring 62 surrounding the upper portion of the plunger 61 and bearing between the top rim of sleeve element 49 and the under surface of arm portion 59, thereby biasing lever arm 56 in a counterclockwise direction, as viewed in FIG. 4. A stop ring 63 is provided on the lower end of plunger 61 to limit upward movement of the plunger substantially to the position thereof shown in FIG. 4, wherein the pin 54 is engageable in a selected locking recess 53. A knob 65 is provided on the innermost end portion of arm element 59 for exerting manual downward force on the plunger 61 against the biasing force of spring 62. When such downward force is exerted on knob 65 the pin 54 is elevated from one recess 53, enabling the arm 52 and die bar 50 to be rotated to another adjusted position thereof wherein pin element 54 may engage in a corresponding detent recess 53.

As shown in FIG. 1, a suitable number of recesses 53 may be provided, corresponding to desired positions of orientation of the female dies 51, 51. In the typical embodiment illustrated, three recesses 53 are provided, said recesses being spaced apart by respective angles of 45° with the intermediate recess located in a transverse vertical plane.

Plate member 34 is formed with a plurality of sets of diametrically-opposed male die apertures 66, 66 located in vertical registry with the various positions of the pairs of female dies 51, 51 established by the settings of pin 54 in the various detent recesses 53. Respective male die assemblies 67 are provided at these various positions, each die assembly comprising a cylindrical lower block 68 on which is adjustably-secured a cylindrical upper block 69, each upper block 69 having a depending central stud portion 70 which is received in the correspondingly-shaped recess centrally-located in the subjacent cylindrical block 68 and locked in adjusted position relative to the lower block by a set screw 71 provided in said lower cylindrical block, as shown in FIG. 11. The upper and lower blocks 69 and 68 are of identical diameters so that their adjoining surfaces are flush with each other. The top end of each upper block 69 is formed with a reduced upwardly-projecting male die element 72, including an upstanding diametrically-extending slot-forming rib 73, the upstanding button element 72 and associated slot-forming rib 73 being receivable in respective cup-shaped recesses 74 provided in the female dies 51, as is clearly shown in FIGURE 13, so that slotted buttons are formed in a sheet metal workpiece 75 acted on by the cooperating male and female dies 67 and 51.

The male die assemblies 67 are slidably-receivable through the apertures 66 in plate 34, as shown in FIGS. 4, 11 and 12. The lower blocks 68 of the male die assemblies are provided with pairs of depending parallel vertical positioning pin elements 75', 75' which are slidably-received in associated pairs of vertical bores 76 provided in the plate member 32, which hold the blocks 68 against rotation. The lower ends of the pairs of pins 75' are engageable with the bottom plate 15, for example, when the machine is in the normal "rest" position thereof shown in FIG. 4, wherein the die assemblies 67 are supported with their top ends located below the horizontal plane of the apertured plate member 34, as shown.

As shown in FIG. 11, the upper die elements 69 are provided with shoulder portions 86 which limit the depth punched by the dies. The angle of the slot formed in the

punched button is predetermined by adjustment of the upper die block 69 with respect to the associated bottom die block 68, the blocks being secured in adjusted positions by means of their associated set screws 71, as above-described.

The top end of the plunger member 21 has a reduced portion 30, as above-mentioned, and the reduced portion 30 is centrally-formed with a pilot bore or recess 87 which rotatably-receives the depending stud element 88 of a horizontally-extending die-supporting bar 89, said supporting bar 89 being provided with the central up-standing post element 90. The top end of post element 90 is formed with a transverse groove 91 adapted to receive the depending diametrically-extending rib portion 92 provided on the bottom end of the plunger member 61, whereby post member 90 may be, at times, keyed to plunger member 61 for the purpose of rotating the die-supporting bar 89 into a position supportingly-engaged beneath a pair of selected male die assemblies 67 in the manner illustrated in FIGS. 4, 11 and 12. The selection of the male die assemblies to be used is performed with the machine in the position of FIG. 4, namely, without the presence of a sheet metal workpiece 75 therein. Under these conditions the male die assemblies are supported by the engagement of their associated pairs of pins 75' with the bottom plate 15. Plate 32 is in a relatively lowered position wherein the die bar 89 is below the plane of the bottom surfaces of the die blocks 68. Under these conditions, the plunger member 61 is depressed by exerting downward force on the knob 65 to engage the key 92 in the groove 91, which allows the die bar 89 to be rotated by rotating the arm 52. This rotates the die bar 89 along with the female die arm 50 to place the die bar 89 beneath the pair of male die assemblies 67 corresponding to the desired orientation of a pair of slotted buttons to be formed in a workpiece. Thus, with key 92 engaged in groove 91 the female die bar 50 is in registry with the male die-supporting bar 89. The supporting die bar 89 maintains the selected male die assemblies 67 in a position sufficiently elevated so that they can cooperate with the female dies 51, 51 when the plates 32 and 34 are elevated by exerting downward force on the treadle pad 29, as will be presently described. Under these conditions, the non-selected male dies remain in relatively lowered positions so that their top ends cannot be elevated above the level of the top plane of plate member 34 when plate member 32 is elevated during the working stroke of the machine.

As will be readily apparent, the male die assemblies 67 which are not supported by the bar member 89 will drop to inoperative positions wherein their top ends will always remain below the plane of the top surface of plate member 34. It will also be understood that the angle of the slot across the button formed by each male die assembly is predetermined by the setting of the upper portion 69 of the male die assemblies 67, each upper male die portion 69 being locked in adjusted position by its associated set screw 71.

An upstanding guide punch 93 of upwardly-convergent or conical shape is mounted on the plate member 34 and cooperates with a similarly located female die unit 94 on the uppermost plate member 37 to form a guide dimple in a strip of sheet metal being punched which is engageable over an upstanding registration pin 95 to properly space the slotted buttons formed at the next operation on the strip of sheet metal. The upstanding guide pin 95 is mounted on an adjustable bar member 96 slidably-supported between a pair of parallel guide rails 97, 97 extending in the direction of longitudinal feed of the workpiece. The guide rails 97, 97 are formed integrally on a plate member 99 projecting forwardly from and rigidly-connected to the front edge of plate member 34. Any suitable locking means may be provided for the adjustable work-positioning bar element 96. For example, the bar element may be provided with a de-

pending stud 100 extending through a longitudinal slot 101 formed in plate member 99 and provided at its bottom end with a wing nut 102 for locking the bar member 96 in longitudinally-adjusted position between the guide rails 97, 97.

As will be apparent, the setting of the bar member 96 and its guide pin 95 determines the spacing between successive sets of punched slotted buttons formed in a strip of metal fed longitudinally, namely, downwardly, as viewed in FIGS. 1, on the plate member 34. Said plate member is provided with a longitudinally-extending fence rail 104 which is adjustable transversely and whose position is determined by the adjustment of a transversely-extending screw 106 provided at its outer end with an operating handle 105 and rotatably-secured at its inner end to the intermediate portion of the fence bar 104. The screw 106 is threaded-engaged through an upstanding bar member 107 secured to the left side edge of plate member 34, as viewed in FIGS. 3 and 4. A lock nut 108 is provided on screw 106 for locking the screw to the fence bar 104 after an adjustment has been made. With the nut 108 loosened, the position of the fence bar 104 may be adjusted by rotating the handle 105.

Handle 105 may be rigidly-secured to the screw 106 in any suitable manner, for example, by the provision of a locking nut 109 on the outer end of the screw member 106.

Rigidly-secured to the outer portions of the fence bar 104 are respective guide blocks 110, 111 which respectively slidably-engage the opposite transverse edges of the plate member 34 and act as guide means for maintaining the fence bar 104 in longitudinal alignment while it is being adjusted transversely on plate member 34.

In operation, a pair of die assemblies 67 is selected in the manner above-described, namely, by depressing the plunger member 61 by means of lever 56 while the plate member 32 is in its lowered position, such as that shown in FIG. 4, to engage key 92 in groove 91, after which lever 56 is rotated to the position corresponding to the desired pair of male die assemblies 67 to be used, after which lever 56 is released to allow the pin 54 to lockingly-engage in the corresponding selected aperture 53. This position bar 89 beneath the selected pair of male die assemblies, as above-described. It also suitably orients the bar 50 carrying the female dies 51 at the same angular position as the bar 89, namely, with the female dies 51 in vertical registry with the selected male die assembly 67. The fence bar 104 is adjusted to the position corresponding to that providing the proper spacing of the punched slotted buttons from the left edge of the strip of sheet metal on which the buttons are to be formed, as viewed in FIG. 2. The strip of sheet metal 75 is then placed between the plate members 34 and 37 with its longitudinal edge engaged against the fence bar 104 and a first set of slotted buttons are stamped therein by stepping on the treadle pad 29 to move plate members 32 and 34 upwardly, first to the position shown in FIG. 11 wherein the plate member 34 and the workpiece 75 engage the female dies 51 and then subsequently to the position of FIG. 12 wherein the selected male dies are forced upwardly against the compressive resistance of the springs 35 to cause male die elements 72 and ribs 73 to form the slotted buttons in the female die recesses.

It will be noted that in accordance with the foregoing description, the plate member 15 constitutes the main horizontal support of the machine, and the post elements 36 constitute vertically-extending guide means rigidly-connecting the top plate 37 to the main supporting plate 15, with the work-receiving table member 34 slidably-engaged on the aforesaid vertical guide means. The plate member 32 constitutes a vertically-movable drive means located between the table member 34 and the main bottom support 15, the drive plate 32 acting through the bar 89 on the selected male die assemblies 67, 67.

FIG. 9 shows a corner turn 115 in an air duct employing a bottom anchoring plate 75 formed with slotted buttons 112 receiving the bottom edges of a plurality of arcuately-curved air-guide plates 114, the buttons 112 being formed in the plate 75 by the device 14 substantially in the manner above-described.

FIG. 10 shows another bottom anchoring plate 75 formed with slotted buttons 112 arranged to receive and support the bottom edges of diagonally-directed parallel louvers 116, said buttons being formed in plate 75 by the device 14 also following a procedure substantially as above-described.

As will be readily apparent, the relationship of the male and female dies may be reversed, if so desired, namely, the dies may be constructed so that the female elements thereof are moved upwardly toward the fixedly-mounted male elements to provide the same results as are obtained with the specific structural arrangement illustrated in the drawings.

While a specific embodiment of an improved machine for forming slotted buttons in sheet metal has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A machine for forming slotted buttons in sheet metal comprising a main horizontal support, a top plate over said support, vertical guide means rigidly-connecting said top plate in vertically-spaced relation to said support movable work-receiving table means between said top plate and support and slidably-engaged with said vertical guide means, drive means between said table means and said support, a plurality of spaced upwardly vertically-extending first die means on said drive means arranged at equal radial distances from a common center, said table means being formed with apertures slidably-receiving and guiding said first die means, a die-support element rotatably-mounted in said top plate on an axis extending through said common center, downwardly-facing second die means on the in said top plate on an axis extending through said common center, downwardly-facing second die means on the die-supporting element located so as to be vertically-registrable with a selected one of said first die means and so as to face the selected one of the upwardly-extending first die means, means to elevate said drive means to bring the selected first and second die means together in work-forming cooperation, one of said die means including a projection having a diametrical transverse rib and the other of said die means being provided with a recess formed to closely-receive said projection.

2. The forming machine of claim 1, and means to rotatably-adjust said projection relative to said one of the die means, said recess in the other die means being formed to receive the transverse rib in a plurality of positions of angular adjustment of the projection.

3. The forming machine of claim 1, and wherein said vertically-movable drive means is slidably-engaged with 60 and held against rotation by said vertical guide means.

4. The forming machine of claim 3, and wherein said apertures are circularly-arranged around said axis, said first die means comprising male die elements each in registry with and receivable in one of said apertures, said second die means comprising a bar member rotatably-connected to said top plate at said common axis and formed with downwardly-facing female die elements.

5. The forming machine of claim 4, and wherein said male die elements are normally supported on said drive means, during a driving stroke, below their operative positions, and movable block means on said drive means engageable below selected male die elements to elevate them to operative positions.

6. The forming machine of claim 5, and wherein said block means extends transversely and is in vertical registry with said bar member.

7. The forming machine of claim 6, and means to at times drivingly-couple said bar member to said block means for simultaneous rotational adjustment, and cooperating locking means on the bar member and top plate for locking said bar member in adjusted position.

8. The forming machine of claim 7, and wherein said male die elements are provided with depending vertical pin means extending slidably through said drive means and being supportingly-engageable with said main horizontal support.

9. The forming machine of claim 7, and wherein said block means is provided with an upstanding central vertical post element at said common axis and said coupling means comprises cooperating key-and-groove means in the post element and bar member.

10. The forming machine of claim 9, and an upstanding male guide die element on said table member and a downwardly-facing female die element on said top plate over said guide die element to form a positioning dimple in a workpiece, and an upstanding guide pin element on the table member located forwardly of and in longitudinal alignment with the male guide die element in the direction of feed, said upstanding guide pin element being shaped to engage in a dimple formed by said male guide die element and the last-named female die elements.
